MUSICAL INSTRUMENT

Ralph W. Fathauer, Cleveland, Ohio

Application June 26, 1940, Serial No. 342,577

4 Claims. (Cl. 84—102)

This invention relates to musical instruments in which means are provided for mechanically playing a predetermined series of notes.

An object of the present invention is to provide an improved musical instrument by means of which a predetermined tune may be played mechanically and repeated as often as desired, and which can be changed to play any other desired tune.

The present invention is an improvement in that type of musical instrument in which a series of hammers are caused to strike a series of note-producing or tone plates, and the improvement includes the provision of novel means for actuating said hammers in a predetermined order and for changing that order at will.

The present invention consists in the novel form, combination and arrangement of parts hereinafter more fully described, shown in the accompanying drawings and claimed.

In the drawings:

Figure 1 is a top plan view of a musical instrument constructed in accordance with the present invention.

Figure 2 is a vertical section on line 2—2 of Figure 1.

Figure 3 is a vertical section on line 3—3 of Figure 2.

Figure 4 is an enlarged central sectional view taken transversely through one of the hammer-actuating wheels; and

Figure 5 is an enlarged perspective view of one of the hammers.

Referring more in detail to the drawings, the present invention includes a bed or base plate 5 on which are mounted a pair of brackets 6 and 6a in which is journaled a horizontal shaft 7. Fixed on and rotatable with the shaft 7 are a plurality of pulley-like wheels 8 having their hubs arranged in contiguous relation and each having spaced peripheral flanges 9 formed with pairs of aligned openings 10 arranged in a circular series about the periphery of the wheel, the pairs of openings being uniformly spaced circumferentially of the wheel, and the openings of each pair being adapted to selectively and removably receive a cross pin 11. While the shaft 7 may be rotated by any suitable means, I have shown the same as provided with a driving motor 12 operatively geared to one end of said shaft 7, the bracket 6a being in the form of a gear-reduction case containing reduction gears which operatively connect the armature shaft of motor 12 with the adjacent end of said shaft 7.

The pins 11 control the playing of the desired

notes, and they may be arranged in any desired pairs of holes in the wheels 8. Upon rotation of the wheels 8, the pins are caused to engage and actuate a series of hammers 13, one of which is arranged in line with each wheel 8. Each hammer comprises a metallic or non-metallic head 14 and a lever 15 pivoted on a rod 16 which is supported in suitable brackets 17 secured to the bed or base 5. Near corresponding ends, the hammers are provided with lateral oppositely extending angular lugs 18 having upwardly projecting outer portions provided with transversely aligned openings 19 for loose reception of the rod 16. The lugs 18 of the hammers are in contiguous relation so that they effectively space the levers 15 the required distances apart. The rod 16 is mounted so as to position the hammers with their shorter ends 20 disposed in the path of the pins 11 carried by the wheels 8.

The brackets 17 also support a stop bar 21 which keeps the hammers 13 normally at a slight distance above the note-producing or tone plates 22, and which also prevents the hammers from striking the plates 22 more than once for each actuation of a hammer, as well as preventing the hammers from damping the tones.

A spring 22' is associated with each hammer for swinging the same in a direction to strike the associated tone plate 22 when the hammer is released from a pin 11 of the associated actuating wheel 8. As shown, each spring 22' is coiled about the rod or shaft 16 between the lugs 18 of said hammer, one end of each spring being engaged with another rod 23 supported by the brackets 17 above the rod or shaft 16, and the other end of each spring being engaged with the adjacent end of the associated hammer 13.

The hammers 13 cooperate with a series of the note-producing or tone plates 22. The plates 22 are mounted on the flanges of a trough 24, suitable strips of felt 25, or the like, being inserted between the plates 22 and the supports, and nails 26 or the like being used to hold the plates 22 in place.

When the pins 11 have been arranged in the desired aligned openings of the wheels 8, the shaft 7 is rotated so to cause rotation of said wheels 8. This will cause the pins 11 in the various wheels 8 to successively engage the corresponding levers 15 and lift the hammers 13. The continued rotation of the wheels 8 causes the pins to slide off of the levers, permitting the respective hammers to drop and strike the stop bar 21 with a movement accelerated by the springs 22'. Due

to the elasticity of the levers 15, which are made of resilient material, the hammers will strike the note-producing plates 22 and cause them to successively emit their characteristic notes. This will be repeated as the wheels are turned, until the entire tune has been played, and the latter may be repeated as often as desired. Having played this particular tune as much as desired the operator can then change the positions of the pins 11 to play any other desired tune in a similar manner.

From the foregoing description, it is believed that the construction and operation, as well as the advantages of the present invention will be readily understood and appreciated by those skilled in the art. Minor changes in the details of construction illustrated and described are contemplated, such as fairly fall within the spirit and scope of the invention as claimed.

What I claim as new is:

1. In a musical instrument, the combination of a plurality of pivoted hammers, and means for mechanically actuating the hammers in a given order to play a tune, said last-named means comprising a plurality of wheels rotatable in unison, one for each hammer, each of said wheels having spaced radially disposed peripheral flanges provided with pairs of transversely aligned transverse openings arranged in a circular series about the periphery of the wheels, and pins removably positionable in selected pairs of said openings for engaging the hammers.

2. A hammer for striking the note-producing means of a musical instrument, comprising a strip of resilient material and a head, the resilient strip being provided near the end remote from the head with oppositely extending lateral angular lugs having upstanding outer ends provided with transversely aligned openings adapted to receive a pivot.

3. In combination, a hammer for striking the note-producing means of a musical instrument comprising a strip of resilient material and a head, the resilient strip being provided near the end remote from the head with a pair of laterally extending angular lugs having upwardly projecting ends provided with transversely aligned openings, a pivot rod passing through said openings, and a spring encircling the pivot rod between the upwardly projecting ends of the lugs, each spring having an upper end anchored and a lower end 20 engaging the adjacent end of said strip of resilient material whereby to swing the hammer downwardly.

4. In a musical instrument, means for mechanically actuating the hammer for striking a note-producing means of a musical instrument, comprising a pulley-like wheel having spaced radially disposed peripheral flanges, said flanges being provided with pairs of aligned transverse openings arranged in a circular series about the periphery of said wheel, and pins removably positionable in said openings.

RALPH W. FATHAUER.
